S. A. Clemens,

Force Pump,

No 11,300,

Patented July 11, 1854.

UNITED STATES PATENT OFFICE.

S. A. CLEMENS, OF SPRINGFIELD, MASSACHUSETTS.

VALVULAR ARRANGEMENT FOR DIAPHRAGM-PUMPS.

Specification of Letters Patent No. 11,300, dated July 11, 1854.

To all whom it may concern:

Be it known that I, STILLMAN A. CLEMENS, of Springfield, in the county of Hampden and State of Massachusetts, have invented a new and useful Improvement in Diaphragm-Pumps; and I do hereby declare that the following is a full and exact description thereof, reference being had to the accompanying drawings, and the letters of reference marked thereon, making a part of this specification, in which—

Figure 1 is a perspective view of the outside of the pump; Fig. 2, a sectional elevation of the same, and Fig. 3, a perspective representation of some of the inner parts of the pump, with the valves, &c., a little separated from each other, but in their proper relative position one above the other. Figs. 4, 5 and 6 represent modifications of the pump and parts.

The same letters refer to like parts in each figure.

(a and b) Figs. 1 and 2 are the two shells or hollow parts which form the body of the pump.

(c) is the pump lever which in Fig. 2 is represented with the handle down.

(d) is the lever stand or fulcrum which forms at its attachment to the top of the pump a packing box for the pump rod (e). The upper and lower shells of the pump are united by flanges, between which is secured the periphery of the diaphragm, which is represented at (f). Above the diaphragm and secured to the pump rod by a nut on its upper side is a perforated disk (g), which has a hub or washer extending downward from its lower face and lying upon the diaphragm (h), where the pump rod passes through it. Below the diaphragm is a disk (i), which is without perforations and is secured to the pump rod by a nut below. That part of the diaphragm which is within a circle covered by the lower disk (i) is perforated, and the lower disk in connection with the perforations in the diaphragm form a valve.

(j) is a check valve made of a circular piece of metal, faced with leather on its lower side for packing, and provided with wire pins projecting downward to keep it over its seat on the top of the inlet tube (k), which last is represented with a screw on its outer surface by which the pump is connected to the supply pipe (l). On the up-

per part of the pump is the discharge pipe (m).

The diaphragm is made of leather or any suitable material, preference being had to that which has flexibility with sufficient strength, and has but little elasticity except by compression on its surface. It is so made and applied that it has a bagging or basin form within the circle of its attachment to the flanges of the upper and lower parts of the pump, to give sufficient capacity to its piston action as the pump rod is raised and depressed.

In Fig. 2 the handle of the base is represented as down, and the pump rod and the parts to which it is attached on the inside are raised. The upward movement of the pump rod first raises the lower or valve disk (i) against the lower surface of the diaphragm (h) and closes the perforations in it which prevents the escape of the water downward. The diaphragm then rests upon the valve (i), which, together with the water on its upper side, is raised, and the latter is forced out of the discharge pipe. While this upward movement is made, the water from the supply pipe raises the check valve (j) and fills the space below the diaphragm. When the upward motion ceases, the check valve closes by its own weight and prevents the return of the water into the supply pipe. As the motion of the pump rod is reversed it first withdraws the periphery of the valve disk (i) from its contact with the lower side of the diaphragm, which uncovers the perforations in the latter, and the periphery of the upper perforated disk (g) is brought down upon the diaphragm, which depresses it, and causes the water from below to pass between the outside of the valve disk (i) and the diaphragm, and thence through the perforations in the latter and in the upper disk into the space above.

Figs. 4, 5 represent a pump in which the same principle of action is applied to the valve and diaphragm as in the one just described, but under a difference of construction. (In Fig. 2 the valve is seen at a' below the diaphragm and is firmly fixed to the piston rod a'. The diaphragm in this case is held between the edges of the disks a³, a⁴ and the valvular openings are in the disks which may be regarded as a part of the diaphragm, and the disks together with the diaphragm have play up and down the pis-

ton between nuts α^5 and α^6 . It will at once be seen upon inspection that the same general character prevails in both forms of valves.

- 5 What I claim as my invention and improvement in diaphragm pumps is—

The mode substantially as set forth of constructing and operating the valve in combination with flexible diaphragms, to wit, 10 the valvular openings being in the diaphragm itself or in a part of the diaphragm

and the valve being attached to and worked by the piston in such manner that the diaphragm shall move to and from the fixed valve and close and open the holes in the 15 diaphragm valve substantially in the manner set forth.

S. A. CLEMENS.
